(57) **CLAIM**

We claim the ornamental design for a clothes dryer, as shown and described.

DESCRIPTION

FIG. 1 is a perspective view of a clothes dryer showing our new design, a window being included on a door;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing the door halfway opened in the left-to-right direction;

FIG. 9 is a front elevation view showing the door halfway opened in the left-to-right direction;

FIG. 10 is a perspective view showing the door fully closed;

FIG. 11 is a front elevation view showing the door fully closed;

FIG. 12 is a perspective view showing the door halfway opened in the top-to-bottom direction;

FIG. 13 is a front elevation view showing the door halfway opened in the top-to-bottom direction;

FIG. 14 is a perspective view showing the door fully opened in the top-to-bottom direction; and,

FIG. 15 is a front elevation view showing the door fully opened in the top-to-bottom direction.

The broken lines in the drawing figures are included for the purpose of illustrating environment and form no part of the claimed design.
